UNITED STATES PATENT OFFICE.

ARTHUR HUGO MÜLLER, OF BLANKENESE, NEAR HAMBURG, GERMANY.

MEANS FOR TOWING BOATS, VESSELS, AND THE LIKE ON WATERWAYS.

Application filed June 27, 1924. Serial No. 722,852.

To all whom it may concern:

Be it known that I, ARTHUR HUGO MÜLLER, a citizen of Germany, residing at Blankenese, near Hamburg, Germany, have invented certain new and useful Improvements in Means for Towing Boats, Vessels, and the like on Waterways, of which the following is a specification.

It has been tried to solve the problem of 10 electro mechanical towing on inland water ways, channels, rivers and the like, by running a traction device along a track suspended over a water way, which traction device is supported on the vessel in 15 such way as to allow of lateral deviations or movements of the ship with regard to the track automatically, while variations of the distance between the ship and the track in vertical plane are accounted for by 20 mechanical adjusting means. However, it is to be noticed, that fluctuations in vertical direction continuously occur owing for instance to irregularities in the position of the track, variations in temperature, or 25 owing to bad erections or fittings and pitching of the ship itself, when high waves are going, or two ships pass by. Such fluctuations particularly on the points of suspension of the track could not heretofore be 30 balanced sufficiently, even if the track had a certain elasticity such when consisting of a chain or cable.

The object of the present invention is to 35 construct means for towing, by which all the requirements of a steady and unobjectionable towing are fulfilled. This object in view the driving mechanism, usually carrying an electromotor is mounted oscillatory or floatingly on the vessel and is balanced in such way that it follows the fluctuations in the distance between the vessel 40 and the track automatically without the latter being burdened by load. In a preferred form the balancing means may be mounted directly on deck of the vessel, which is particularly of advantage where high stands, which take away a great 45 amount of space on deck, are avoided, and in this preferred form the balancing means 50 may be so constructed as to avoid the electromotor to be arranged on the driving mechanism.

In the drawing two modes of construction for carrying out the invention are 55 shown.

Fig. 1 is an elevation of one part of a plant, and

Fig. 2 a plan for illustrating the invention.

Fig. 3 is a similar view as Fig. 1 of a 60 modification and

Fig. 4 a plan of the construction shown in Fig. 3.

The driving mechanism constructed as 65 a driving mechanism *a* is adapted to run along the track *b* and has an upper part *c* for being properly guided on the track. In the construction shown the track *b* is constructed similar to a rack having teeth or pins *b*¹ with which the teeth of the sprocket- 70 wheels *c*¹ engage. The driving mechanism *a* is floatingly linked at *d* to two links or levers *e*, *f*, pivoted intermediate of the ends to a bracket *g* and carrying at their free ends a counterweight *h* to balance the weight of 75 mechanism *a*. The mechanism *a*, the two links constructed as double armed levers *e*, *f*, and the weight *h* form a parallelogram so as to secure the correct vertical position 80 of the driving mechanism no matter to what height it is raised. The bracket *g* is rotatably supported about a central axis on a four legged stand *i* on the deck of the vessel, the legs being preferably made in sections *i*¹ and *i*² telescoping into one another so as to be 85 adjustable in their length in well known manner. By the levers *e* and *f* being oscillately mounted on the bracket *g* the member *a* can move automatically up and down according to the fluctuations of the height of 90 the track *b*, the counterweight *h* continuously tending to raise the mechanism *a* up to the track, and the bracket *g* being rotatably mounted on the stand *i* the mechanism *a* is 95 adapted also to oscillate horizontally about the central axis of the bracket *g*. This is particularly of importance when two vessels being towed in different directions meet and are allowed to pass one another; the levers *e*, *f* will then turn out angularly to the center line of the vessel into the position for 100 instance shown in Fig. 2 in dotted lines.

The levers *e*, *f*, form a frame, which is pivotedly mounted on the bracket *g* and carries on one end the driving mechanism *a* 105 and on the other end the weight *h* balancing the trolley so as to raise it up to the track independent of the variations in its height.

In the modification shown in Figs. 3 and 110 4 means are provided to avoid the stand *i*

which takes away a comparatively large part of the space on deck. In this modification instead of two double armed levers the link carrying the driving mechanism is formed only by a single arm c^x pivotally connected to a bracket g^x directly mounted on deck of the vessel. The weight h^x is mounted on an arm c^{x1} also pivotally attached to the bracket g^x opposite the arm c^x , and carries a comparatively small stand f^x . The upper end of this stand is connected with the arm c^x intermediate of its ends by a sectional tie-rod k between the sections of which a stretching screw m is inserted adapted to shorten or lengthen the tie-rod. By shortening the tie-rod the driving mechanism a attached to the end of the arm c^x is raised to such a height that it can be moved along the track b . The counter-weight h^x has here the same effect as the counterweight h described with reference to Figs. 1 and 2 so as to account for fluctuations in the height of the track.

In this modification (Figs. 3 and 4) it is not necessary to mount the electro-motor for towing or drawing the ship on the driving mechanism as is usually done in plants of this description heretofore, but it is mounted here on the arm c^{x1} , thus also serving as a counter weight. The driving mechanism a can be made very low. This modification is very convenient for enabling the vessel to be towed below bridges or on other tracks which cannot be mounted very high. Particularly in passing locks this arrangement will be of great value where the track for the underwater is very high, and when raised up to the upper water will be low in comparison to the level of the water. The arm c^x together with the driving mechanism a will be raised or lowered by turning the stretching screw m in one or the other direction. For small fluctuations in the height of the track even under bridges which are not too low the automatical balancing of the weight will be sufficient.

Instead of mounting the bracket g^x directly on the deck it might be mounted on a screw jack n of known construction similar to such as is used for raising road vehicles. The arms c^x and c^{x1} together with the stand f^x and the tie-rod k form the frame pivotally mounted on the bracket g^x and carrying on one end the balance-weight, and on the other end the trolley raised up to the track by said weight as explained above.

I claim:

1. The combination with a vessel, of an overhead track, driving mechanism adapted to run along the overhead track and mounted floatingly on the vessel, and means

to automatically balance the driving mechanism as to its height so as to account for variations in the height of the track.

2. The combination with a vessel, of an overhead track, a bracket on said vessel, a frame oscillatorily mounted on said bracket, a driving mechanism pivotally attached to one end of the frame and adapted to run along the overhead track, and a counter-weight on the other end of the frame to balance the driving mechanism for engaging the track.

3. The combination with a vessel, of an overhead track, a bracket on said vessel, a frame oscillatorily mounted on said bracket and comprising a link pivotally connected at one end with the bracket, a weighted member also pivotally connected with the bracket and means to adjustably connect said member with said link, a driving mechanism pivotally attached to the other end of said link and adapted to run along the overhead track.

4. The combination with a vessel, of an overhead track, a bracket on said vessel, a frame oscillatorily mounted on said bracket and comprising a link pivotally connected at one end with the bracket, a weighted member also pivotally connected with the bracket, a tie-rod adjustable in length and connecting said weighted member with said link at a point intermediate of its ends, a driving mechanism pivotally attached to the other end of said link and adapted to run along the overhead track.

5. The combination with a vessel, of an overhead track, a bracket on said vessel, a frame oscillatorily mounted on said bracket and comprising a link pivotally connected at one end to the bracket, a weighted arm also pivotally connected at one end to the bracket, a frame on said arm, a sectional tie-rod connecting the upper end of the frame with said link intermediate of its ends, a turn buckle between the sections of the tie rod for adjusting its length, and a driving mechanism pivotally attached to the free end of the link and adapted to run along the overhead track.

6. The combination with a vessel, of an overhead track, a bracket on said vessel, a support member oscillatorily mounted on said bracket, a driving mechanism pivotally attached to one end of the member and adapted to run along the overhead track, a counter-weight on the other end of the member to balance the driving mechanism when engaging the track, and means for adjusting the height of the bracket.

ARTHUR HUGO MÜLLER.
